S. ALLINGHAM ET AL

CONVEYER FOR CARRYING FIBROUS MATERIAL

Filed Feb. 26, 1926

UNITED STATES PATENT OFFICE.

SIDNEY ALLINGHAM, OF LONDON, AND MAURICE SOENENS, OF BURY ST. EDMUNDS, ENGLAND, ASSIGNORS TO ROBERT BOBY LIMITED, OF BURY ST. EDMUNDS, ENGLAND, A BRITISH COMPANY.

CONVEYER FOR CARRYING FIBROUS MATERIAL.

Application filed February 26, 1926, Serial No. 90,777, and in Great Britain October 8, 1924.

This invention relates to machines for breaking, scutching, opening, combing, or decorticating fibrous materials such as stalks of flax, and its object is to provide improved means for gripping the said fibrous materials while being carried in straight lines through the machine and while being submitted to the action of the operative devices therein.

10 According to this invention the stalks, leaves or other fibrous materials while their free ends are undergoing treatment are held at their other ends between a rubber or other flexible belt having inclined sides and a jointed channel-shaped chain so arranged that the belt enters the channel of the said chain and the grip is exerted across the mouth of the channel or at the mouth and sides thereof. The necessary resiliency is obtained from the width of the belt, and may be increased by the spring of the metal of the channel. The belt and chain travel at the same speed and have no movement relatively to each other while carrying the fibrous material in a straight line, and no pressure is exerted by the belt and chain on the said material in a direction towards or from the base or web of the channel. The belt may be triangular in cross section, with the apex of the triangle directed towards the base of the channel, or the apex may be truncated or rounded off. The opening of the channel may be directed upwardly, downwardly, or laterally at any angle, while carrying the material. The chains are made with spigots and socket joints so as to minimize the possibility of the fibrous material being caught in the joints of the chains, especially when the chains open out in passing around polygonal driving or carrying rollers. The stalks can be laid on the chain immediately after passing the polygonal roller or sprocket wheel at the feeding end of the machine, and the belt is then pressed into the channel of the chain by another roller before the belt and chain reach the working zone, bending the end of each stalk into a zigzag formation so that it is held with sufficient firmness without the use of a series of rollers to support the chain. In machines in which one end of a stalk or leaf is gripped by the carrying means while the

other end is being treated, and the hold on such stalk or leaf is then reversed to allow of treatment of the first named end in its turn, the belt and chain close on such stalk or the like when fed into the machine, bending it into a zigzag shape and separating to release it when required by passing in opposite directions around pulleys.

In order that the said invention may be clearly understood and readily carried into effect, the same will now be described more fully with reference to the accompanying drawings, in which:—

Figure 1 represents in cross section a belt applicable to the practice of this invention.

Figure 2 represents a portion of the chain in central longitudinal section.

Figure 3 is a plan of the chain seen in Figure 2.

Figure 4 is a cross section of the chain taken on the line 4—4 in Figure 2.

Figure 5 is a cross section of the belt, the chain, and the channel supporting the chain, assembled in their relative positions for operation.

Figure 6 is a side elevation illustrating a modified arrangement in which the members of the chain, instead of being pinned to each other, are riveted to a flexible carrying belt.

Figure 7 is an end elevation of the link represented in Figure 6.

Figure 8 is a plan of the said link.

The belt may consist mainly of soft rubber A with a core B of relatively hard rubber, and its operative surface is bevelled off or inclined, for example in the manner illustrated at a¹. Each link C of the chain has at one end a widened portion or socket c¹ to embrace one end of the adjacent link, and the base of the link has at its other end a bored enlargement or boss c² of somewhat cylindrical form for the reception of a pin D connecting two adjacent links. E (Figure 5) indicates a rigid supporting channel in which the belt and chain travel together at the same speed while the fibrous materials are being carried through a machine and their free ends are undergoing treatment therein, their other ends being bent into a zigzag shape and gripped between the sides of the belt and the flanges of the

chain as indicated in dot-and-dash lines at F in Figure 5, until the belt and chain are separated to release the said materials.

In the modification illustrated in Figures 5 to 8, the boss c², pin D, and rigid supporting channel E are omitted. Each link C is independently secured to a flexible belt G by any suitable means, for example by bifurcated rivets H. The overlapping or socketed part c¹ of the link is of such length that any slight movement tending to longitudinal separation of the links occurring by reason of stretching of the belt G is immaterial.

This invention will be found particularly useful in connection with machines adapted for straight continuous feeding of the fibrous materials in such manner that the said materials are successively exposed to the action of consecutive operating devices, as for instance in cases where the materials are automatically transferred from one carrying device to another with or without reversal of the position of the materials to expose untreated portions thereof to the action of the operating devices, as distinguished from machines in which the materials are held in clamps while traveling through the machine. In straight continuous feeding machines with flexible chains hitherto employed, it has been usual to support the chain with a number of small rollers, which rollers were liable to be clogged with dust, tow, and long loose fibres, thus necessitating frequent stoppages of the machine for cleaning the rollers; and the rollers added considerably to the weight and cost of the machine. Where such rollers were employed, it was not practicable to scutch what is known as short flax (which must be scutched very close to the holding or carrying device) owing to the said rollers occupying the space close to the chain. By the use of this invention it is possible to scutch flax of practically any length, however short, and when the materials have been placed across the chain and the belt forced into the channel of the chain by a single roller, they can be carried on to any length of travel that may be desired without the necessity of employing supporting roll-

ers to keep the belt and chain in proper relation to each other.

What we claim and desire to secure by Letters Patent of the United States is:—

1. A machine for the purpose specified comprising a conveyer for carrying fibrous materials in a straight line while being subjected to the actions of operative devices of the machine, said conveyer consisting of a series of channel shaped members associated so that their walls form a composite channel, the members being adapted to be moved bodily in a direction longitudinally of the channel, and a resilient member having substantially parallel portions on its side walls for engagement with respective side walls of the channel members moving in a continuous path and adapted to be pressed into the channel for securing the fibrous material therein, said resilient member being securely held in the channel by its contact with the side walls of the channel members due to its resiliency and being arranged to travel with the channel shaped members throughout a portion of their travel and thereafter to be withdrawn from the channel shaped members for movement through its continuous path of travel.

2. In a machine for the purpose specified comprising a conveyer for carrying fibrous material in a straight line while being subjected to the action of the operative devices of the machine, the construction of said conveyer including an endless flexible carrying belt, a series of rigid channel shaped members secured on the said belt, in combination with a gripping belt of flexible material such as rubber having inclined side walls adjacent the face which first engages the fibrous material, and means for pressing said gripping belt into said channel shaped members when first taking up said fibrous material and before reaching the working zone whereby the grip on said material is exerted across the mouth of the channel, and is automatically maintained while the said materials are being carried through the working zone.

SIDNEY ALLINGHAM.
MAURICE SOENENS.
